[57] **ABSTRACT**

This device is an umbrella and an umbrella tree frost

cover which is operable to open and to closed position by a valve controlled pneumatic pressure mechanism. It has an umbrella rod to which umbrella ribs are pivotally secured and it includes an inner two-way hoist cylinder in which the umbrella rod is secured to a piston rod and piston actuated by the pressure to push up the umbrella ribs and an attached cover from out of an outer base cylinder, and the pressure may then be exerted on the top of the piston to retract the umbrella ribs and cover the outer base cylinder.

When used as a tree frost cover, the outer base cylinder is partly embedded in the ground adjacent the trunk of the tree it will cover, and when operated, the umbrella portion extends over the top of the tree and has depending tree frost cover portions which droop down from the umbrella portions to adjacent the ground. It may be made in various sizes to fit different size trees.

In the umbrella form, the ribs are tempered and of inverted U-shape, and support the umbrella cover in usual umbrella position. In tree frost cover form, the ribs extending from the inverted U-shaped tempered ribs beyond the umbrella portion are flattened out, not tempered, and are flexible, so that the tree frost cover thereon droops down to below the lower tree branches, thus protecting the fruit against frost.

UMBRELLA AND UMBRELLA TREE FROST COVER

OBJECTS OF THIS INVENTION

It is an object of this invention to provide an umbrella tree frost cover that may be secured closely adjacent a tree it is to protect against frost, which is quickly openable to operative position by pressure, pneumatic or otherwise, and which is similarly pressure operated to closed position.

A further object of this invention is to provide an umbrella tree frost cover which has both an umbrella portion for extending over a tree and in addition has a tree-side frost protecting portion drooping down from the umbrella portion attached thereto.

A further object of this invention is to provide an umbrella tree frost cover which is stored in a base cylinder secured adjacent the tree it is to protect when needed, wherein the umbrella tree frost cover may be quickly operated to protective position by pressure, and as quickly operated back to stored position by the same mechanism.

Still a further object of this invention is to provide both a large umbrella and an umbrella tree frost cover, wherein the umbrella tree frost cover form covers both the top of the tree and the lower sides of the tree, and wherein the umbrella form has the identical pressure operated mechanism as the umbrella tree frost cover form, and differs therefrom by merely omitting the frost cover and the flexible ribs for the lower sides of the tree, wherein the umbrella top form has tempered inverted U-shaped umbrella ribs, and wherein the umbrella tree frost cover form has the identical U-shaped tempered umbrella ribs and in addition flexible, untempered flat rib portions integrally extending from each of the tempered U-shaped ribs, the flat ribs carrying the frost cover extending down the lower sides of the tree.

A further object of this invention is to provide an umbrella tree frost cover having a manually controllable pressure mechanism for operating the umbrella tree frost cover from stored position to cover position and from cover position to stored position, and, further, wherein a thermostat control may be added to the manual control for actuating the manual control when the temperature drops to a predetermined point to operate it to cover position, and then when the temperature rises again to a predetermined point, it operates the cover to stored position.

Yet a further object of this invention is to provide an improved umbrella tree frost cover over the tree protector devices shown particularly in the following listed U.S. Pats: Conrad, No. 645,890; Liljegren, No. 1,072,340; Honstedt, No. 1,351,249; and Savage, No. 2,405,452; and, in general, an improvement over all the prior art.

BRIEF DESCRIPTION OF THE FIGURES

With the above and related objects in view, this invention consists in the details of construction and combination of parts, as will be more fully understood from the following description, when read in conjunction with the accompanying drawings, in which:

FIG. 1 is an elevational view of the umbrella tree frost cover form of the invention in storage position.

FIG. 2 is an elevational view in partly opened position.

FIG. 3 is an elevational view in fully opened position.

FIG. 4 is an elevational view of the umbrella form only of this invention, in fully opened position.

FIG. 5 is an enlarged view of the invention in initial opening position.

FIG. 6 is a vertical sectional view, partly broken away, on still larger scale.

FIG. 7 is a vertical sectional view, also on the larger scale, fully opened and partly broken away.

FIGS. 8 and 9 are cross-sectional views of line 8-8 and line 9-9 on FIG. 6.

FIG. 10 is a large sectional view on lines 10-10 of FIGS. 3 and 4, showing the U-shaped tempered umbrella rib position.

FIG. 11 is a large scale sectional view on line 11-11 of FIG. 3, showing the flat, untempered extending rib portion.

DETAILED DESCRIPTION OF THE INVENTION

There is shown at 10 the umbrella tree frost cover form of this invention is mounted in operative position adjacent a fruit tree 12 that it is designed to protect against frost. The umbrella invention shown at 14' in FIG. 4 is identical with the part of the umbrella tree frost cover invention 14 above the line A-A in FIG. 3, and accordingly identical parts of both forms of the invention are identified by the same reference numbers, and when they differ only in size, the reference numbers are primed.

The umbrella ribs 16 are U-shaped in cross section, as shown in FIG. 10, with the umbrella cover 18 resting on the ends of the U-legs 19 of the U-ribs 16. These U-ribs 16 are of tempered metal so as to support the umbrella cover 18 on the U-legs 19 when opened in the conventional umbrella position, as in FIGS. 3 and 4. In FIG. 4, the tempered, U-shaped ribs 16 terminate at the bottom edges of the umbrella cover 18 in a conventional manner, but in FIGS. 2 and 3, a tree frost cover portion 22 extends downwardly when fully opened.

The extending portions 20 of ribs 16, which may be integral, are flattened out and untempered, so as to be flexible and hang down from the tempered U-shaped ribs 16, and tree frost cover 22 extending down from umbrella cover 18 is supported by and attached to extending flexible, untempered, flat ribs portions 20. It is the presence or absence of these untempered, flattened, flexible rib portions 20 that makes the difference between the umbrella tree frost cover form 14 shown in FIGS. 1, 2 and 3 and the umbrella form 14' shown in FIG. 4 as mounted on an outdoor table 24.

The operating mechanism for storing, ejecting and retracting the umbrella 14 or the tree frost cover 10 consists of a base cylinder 26, which, in the case of the tree frost cover 10, is partly embedded in the ground 27 adjacent the trunk of the tree 12, which it protects, as shown in FIGS. 1, 2 and 3. In the case of the umbrella 14', the base cylinder 26 is suitably supported in the desired location, as on an outdoor table 24. Suitably secured to the bottom 28 of the base cylinder 26 is a concentric inner two-way hoist cylinder 30.

The top portion 38 of base cylinder 26 flares outwardly somewhat, and a cap 40 for closing the flared top 38, to protect against rain when in closed position, is secured on the top end of the piston rod 42 which extends through a bushing 44 into the inner two-way hoist cylinder 30. A piston 46 with lower and upper piston rings 48 and 50 is secured on the bottom of the piston

rod 42 within the inner two-way hoist cylinder 30, and pressure from pneumatic pressure conduit 52 to the bottom of inner cylinder 30 will move piston 46 and piston rod 42 upwardly until it is stopped by cushioning spring 54 secured to the bottom of bushing 44. A second pressure conduit 56 leads to the top of cylinder 30 above the limit of travel of piston 46 to activate the piston 46 and piston rod 42 in a downward direction. The pressure conduits 52 and 56 and valve 58 are connected to a readily replaceable pneumatic pressure tank 60 and operable by manual control valve handle 62 to either conduit 52 or 56 while bleeding the pressure from the non-pressured conduit to thus move and hold the piston rod 42 in either retracted, closed storage position, or extended open position.

The inner ends 64 of U-shaped ribs are pivotally secured at 66 to radially projecting ears 68 of a collar 70. This, in turn, is secured to an intermediate cylinder or umbrella rod 72 of plastic or other suitable material. This cylinder 72 surrounds inner, two-way hoist cylinder 30 and is secured to piston rod 42 to ride up or down therewith to pull the tempered U-shaped ribs 18, and also the flat untempered flexible ribs 20 in the tree frost cover form up and out of the base cylinder 26, or pull them back down into the cylinder 26. The flared top 38 of cylinder 26 guides the ribs and cover back into the cylinder 26. Intermediate umbrella rib cylinder 72 is longitudinally slotted at 73 to pass over upper pressure conduit 56. The rib pivoting collar 70 is notched at 74 so as to pass about the upper pressure conduit 56, which also serves to prevent the umbrella 14' and tree frost cover 14 from rotating freely about the axial center. The intermediate umbrella rod cylinder 72 is annularly spaced from outer base cylinder 26 by an upper spacing disc 32 secured thereto near its bottom, and a second and lower spacing disc 34 is flexibly attached to upper disc 32 by a flexible plastic connector 36 so that the lower disc 34 will still provide spacing when the upper disc 32 is in the area of the flared top 38, as shown in FIG. 7. The discs 32 and 34 are also notched at 74 to pass about pressure conduit 56.

OPERATION

When pneumatic pressure is delivered into cylinder 30 below piston 46, and simultaneously bled from above piston 46, piston 42 moves to its top limit against cushioning spring 54, simultaneously moving intermediate cylinder or umbrella rod 72 to pull up the ribs 18 and 20 and their attached umbrella cover 18 and thus push flexible ribs 20 and tree frost cover 22 from out of the base cylinder 30 to the extending first position shown in FIG. 2.

Then, as the cylinder or umbrella rod 72 moves from position in FIG. 2 to that of FIG. 3, the flexible ribs 20 and tree frost cover 22 move down to frost protecting position of FIG. 3 depending from the umbrella ribs 16 and umbrella cover 18.

In the umbrella form 14' of FIG. 4, the operating mechanism is shorter, due to the absence of the flat, flexible extending rib portions and tree frost cover positions, but is otherwise identical in construction and operation.

With the umbrella 16' or tree frost cover 14 in extended position, it is held in such position by the tem-

pered U-shaped ribs 16 as well as by the weight of the umbrella and tree frost cover, while, when retracted into the base cylinder, it also remains in position. Hence, the valve 58 may be a conventional three-way valve for applying pressure in either direction while bleeding it in the other direction, and when in position, may then be set to bleed the pressure from the pressure side, while closing off the pressure tank 60 and preventing loss of pressure therefrom as pressure is not needed to maintain the umbrella or cover in either open or closed position. In the case of the tree frost cover, a conventional thermostatically controlled device may be added to automatically open the tree frost cover when the temperature drops below a preset point, and to again close it when it rises above a slightly higher preset point, to provide automatica frost protection.

In the drawings, like numbers refer to like parts, and for the purposes of explication, marshaled below are the numbered parts of the improved Umbrella Tree Frost Cover of this invention:

- 10 umbrella tree frost cover
  - 12 fruit tree
  - 14 or 14' umbrella invention
  - 16 U-shaped tempered ribs
  - 10 umbrella tree frost cover
  - 12 fruit tree
  - 14 or 14' umbrella invention
  - 16 U-shaped tempered ribs
  - 18 umbrella cover
  - 19 U-legs of ribs 18
  - 20 flat, untempered, flexible extending ribs of 16
  - 22 tree frost cover portions extending from umbrella cover portions 18
  - 24 outdoor table (on which umbrella base cylinder 26 is mounted)
  - 26 or 26' base cylinder
  - 27 ground
  - 28 bottom floor of base cylinder 26
  - 30 concentric inner two-way hoist cylinder
  - 32 upper spacing disc secured to intermediate 72
  - 34 lower spacing disc
  - 36 flexible plastic connection between 32 and 34
  - 38 outwardly flared top of base cylinder 26
  - 40 cap to close flared top 38
  - 42 piston rod
  - 44 bushing at top of inner cylinder 30
  - 46 piston on piston rod 42
  - 48 lower piston ring
  - 50 upper piston ring
  - 52 lower pressure conduit
  - 54 cushioning spring secured under bushing 44
  - 56 upper pressure conduit
  - 58 pressure valve
  - 60 replaceable pressure tank
  - 62 valve control handle
  - 64 inner ends of ribs 16
  - 66 pivot pins for 64
  - 68 pivot ears on 70
  - 70 collar mounted on intermediate cylinder (or umbrella rod) 72
  - 72 intermediate cylinder or umbrella rod
  - 73 longitudinal slot in cylinder 72
  - 74 notch in collar 70
- Although this invention has been described in considerable detail, such description is intended as being il-

lustrative rather than limiting, since the invention may be variously embodied, and the scope of the invention is to be determined as claimed.

Having thus set forth and disclosed the nature of this invention, what is claimed is:

1. A pressure operable umbrella (10) comprising a base cylinder (26) having a base floor (28) at its bottom, an inner two-way hoist inner cylinder (30) concentric with said base cylinder (26) and secured to the floor (28) of said base cylinder (26), a piston rod (42), a piston (46) secured thereon at its lower end and vertically reciprocable within said inner two-way hoist cylinder (30), a bushing (44) sealing the upper end of said inner cylinder (30), said piston rod (42) reciprocating through said bushing (44), piston cushioning means (54) secured to said bushing (44) within said inner cylinder (30), an intermediate umbrella rod cylinder (72) vertically reciprocable about said inner cylinder (30), said intermediate cylinder (72) being secured to said piston rod (42) adjacent its top end, annular means (32, 34, 36) about said intermediate cylinder (72) spacing said intermediate cylinder (72) within said outer base cylinder (26), a collar (70) secured about said intermediate cylinder (72) adjacent to and above said spacing means (32, 34, 36), a plurality of umbrella ribs (16) pivotally (66) secured to said collar (70) and extending up within said outer base cylinder (26), an umbrella cover (18) on said ribs (16) receivable within said outer base cylinder (26), controllable (58, 62) pressure means (60), and pressure conduit means (52, 56) from said controllable pressure means to said inner two-way hoist cylinder (30) to below said piston (46, 48) and to above said piston (46, 50) for controllably reciprocating said piston rod (42) and intermediate umbrella rod cylinder (72) to eject and retract said umbrella ribs (16) and umbrella cover (18) from and to within said outer base cylinder (26).

2. The umbrella of claim 1, said base cylinder (26) having an outwardly flared open top (38) for guiding

the retracting ribs (16) and cover (18) thereinto, and a cap (40) secured on the top end of said piston rod (42) complementary to said base cylinder flared open top end (38) to close said flared open top end (38) when in down position.

3. The umbrella of claim 1, said annular spacing means comprising a pair of annular spacing discs (32, 34) about said intermediate cylinder (72), said upper disc being secured to said intermediate cylinder (72), said lower disc (34) being flexibly suspended from said upper disc (32) adjacent the lower end of said intermediate cylinder (72).

4. The umbrella of claim 1, said pressure conduit means (56) to above said piston (46, 50) extending closely adjacent to said intermediate cylinder (72), said discs (32, 34) and said collar (70) being notched and said intermediate cylinder (72) being longitudinally slotted (73) to ride over said upwardly extending pressure conduit (56) and prevent rotation of said collar (72) and thus of said umbrella.

5. The umbrella of claim 1, said ribs (16) being tempered to support said umbrella cover (18) when ejected to umbrella position, said tempered ribs (16) extending from their pivotal connections (66) to said collar (70).

6. The umbrella of claim 5, said tempered ribs (16) being U-shaped (19).

7. The umbrella of claim 6, the U-legs (19) of said U-shaped umbrella ribs (16) being in supporting contact with said umbrella cover (18).

8. The umbrella of claim 5, and flexible, untempered rib portions (20) extending from the ends of each tempered rib (16), said umbrella cover (18) extending over said untempered rib portions (20) providing tree frost cover means (22).

9. The umbrella of claim 8, said tempered ribs being U-shaped and having their U-legs (19) providing cover (18) contact support, said untempered rib portions (20) being flat and flexible.
